UNITED STATES PATENT OFFICE.

WILLIAM H. ROBERTS, OF DETROIT, MICHIGAN, ASSIGNOR TO D. H. ROBERTS, OF DETROIT, MICHIGAN.

VALVE.

No. 865,318.

Specification of Letters Patent.

Patented Sept. 3, 1907.

Application filed October 30, 1905. Serial No. 286,103.

To all whom it may concern:

Be it known that I, WILLIAM H. ROBERTS, a citizen of the United States of America, residing at Detroit, in the county of Wayne and State of Michigan, have invented certain new and useful Improvements in Valves, of which the following is a specification, reference being had therein to the accompanying drawings.

The invention relates particularly to a gas valve especially designed for use in connection with gas stoves or ranges and consists in the peculiar construction of the valve, and, further, in the novel arrangement and combination of its parts as more fully hereinafter set forth.

In the drawings, Figure 1 is a vertical central section through the valve; Fig. 2 is a view in elevation thereof; 15 and Fig. 3 is an enlarged sectional view, showing the parts in a position different than illustrated in Fig. 1.

A represents the valve casing, open at both ends as indicated and provided with a threaded nipple B adapted to be attached to the gas supply conduit and to form the 20 means of communication between the latter and the valve interior. The opening in the casing is preferably tapered and the rear portion of the casing is slightly reduced and externally screw-threaded and the threaded portion is recessed or cut away, as at D, for a purpose to 25 be hereinafter set forth.

E represents a tapered cock fitting within the tapering opening in the casing, extending preferably flush with the discharge end of the casing and terminating at its opposite end in a handle section F, projecting some 30 distance beyond the casing. The extremity of the handle portion is squared, as at G, to receive a suitable handle, as H, in this instance a wheel having an opening extending therethrough corresponding in form to the squared portion.

35 A relatively large reservoir or chamber I is formed in the cock extending from a point above the nipple B throughout its forward portion and terminating in a restricted discharge opening J. In this instance, the discharge end is formed by a jet nozzle K threaded within 40 the discharge end of the cock and having a conical portion L immediately adjacent the discharge end, forming a seat for the valve M.

O represents a gas inlet formed in the cock adapted to be brought into and out of registration with the nipple 45 B upon the turning of the cock to permit of the discharge of the gas through the valve.

P represents a bore leading from the chamber I in the cock outwardly through the rear portion of the latter,

said bore being threaded internally to receive a threaded plug Q which carries the needle valve M. This latter plug is adapted to project beyond the handle section of the cock and is provided with a cross slot, as R, by means of which, through suitable implement, the valve may be turned to throw it in proximity to or away from its seat, for the purpose of controlling the discharge of 55 the gas.

S represents a cap adapted to be threaded upon the extremity of the handle section of the cock and serves as a protector for the end of the plug Q and as a lock for the handle, the cap bearing against the handle and 60 clamping the latter against a shoulder T upon the cock formed for that purpose.

The tapered cock is held in contact with the walls of the casing by means of a cap or coupler U, which engages the threaded section C on the casing and a split 65 spring washer V interposed between the end of the cap and a shoulder W upon the cock, the shoulder being preferably at some distance from the end of the threaded section C, so as to allow for wear between the plug and the valve casing.

X represents a pin fixed upon the cock adapted to turn within the recess D, the recess being so proportioned as to permit the turning of the cock a sufficient distance to bring the gas inlet O into and out of registration with the threaded nipple, so as to open the valve 75 or close the latter, as desired.

From the description of the valve, the operation will be apparent and requires no further explanation. Attention is directed to the fact that by means of the cap U and the split spring washer, a simple and efficient 80 means of holding the cock within the valve casing is provided; furthermore, any desired tension may be placed upon the cock for the purpose of taking up play between the parts by merely turning the cap. The detachable nozzle section, while not essential, is desirable, as it affords means whereby the valve seat may be readily cleansed or replaced when worn.

What I claim as my invention is:—

1. In a valve, the combination with a valve casing provided with an inlet and having a threaded extension at one end, of a longitudinally bored plug valve seated in the casing and having an inlet arranged to communicate with said casing inlet, one end of said valve projecting and having a shoulder outside of said casing, a coupler sleeved on the projecting end of said plug and engaging the threaded extension of said casing, a resilient member sleeved on said plug and engaged by said shoulder and said coupler, a

needle valve in said plug valve and a hand operated member for adjusting said plug valve, for the purpose described.

2. In a valve, the combination with a valve casing provided with an inlet, of a plug valve seated within the 5 casing and extending outside thereof having a discharge passage and an inlet port adapted to establish communication between said passage and the casing inlet, a needle valve within the plug controlling the discharge, an operating member for the plug valve sleeved on the out-

ward extension thereof, and a cap covering the end of the 10 needle valve and having a screw threaded engagement with the plug extension for retaining said operating member.

In testimony whereof I affix my signature in presence of two witnesses.

WILLIAM H. ROBERTS.
